US0D1073492S

(12) **United States Design Patent** (10) Patent No.: **US D1,073,492 S**
(45) Date of Patent: ** May 6, 2025

(54) **METAL DETECTOR**

(71) Applicant: **CONRAD DEDEKTÖR
TEKNOLOJILERI VE
MÜHENDISLIK HİZMETLERİ
TICARET LIMITED SIRKETİ,
İstanbul (TR)**

(72) Inventor: **Erol Gökalp, Istanbul (TR)**

(**) Term: **15 Years**

(21) Appl. No.: **35/520,360**

(22) Filed: **Dec. 11, 2023**

(80) **Hague Agreement Data**

Int. Filing Date: **Dec. 11, 2023**

Int. Reg. No.: **DM/235814**

Int. Reg. Date: **Dec. 11, 2023**

Int. Reg. Pub. Date: **Mar. 22, 2024**

(51) LOC (15) Cl. 10-04

(52) U.S. Cl.

USPC **D10/47**

(57) **CLAIM**

The ornamental design for metal detector as shown and described.

DESCRIPTION

1. Metal detector
- 1.1 Perspective view
- 1.2 Perspective view
- 1.3 Detailed view
- 1.4 Left side perspective view
- 1.5 Top perspective view
- 1.6 Top perspective view
- 1.7 Side view
- 1.8 Bottom perspective view
- 1.9 Detailed perspective view
